CLAIM

The ornamental design for a support bracket, as shown and described.

DESCRIPTION

FIG. 1 is a frontal perspective view of a support bracket in accordance with a first embodiment of the present invention; FIG. 2 is a first side view of the support bracket of FIG. 1, the second side being a mirror image; FIG. 3 is a bottom view of the support bracket of FIG. 1; FIG. 4 is a top view of the support bracket of FIG. 1; and, FIG. 5 is a front view of the support bracket of FIG. 1. The broken line showing in FIGS. 1, 3, and 5, of four screw holes and inner surface features in the claim is included for the purpose of illustrating portions of the support bracket and forms no part of the claimed design.

1 Claim, 3 Drawing Sheets
